(57) **CLAIM**

The ornamental design for an electrophoresis wedge-well comb, as shown and described.

DESCRIPTION

FIG. 1 is a front, top and side perspective view of an electrophoresis wedge-well comb, according to an exemplary embodiment;

FIG. 2 is a back, top and side perspective view of the electrophoresis wedge-well comb of FIG. 1;

FIG. 3 is a front view of the electrophoresis wedge-well comb of FIG. 1;

FIG. 4 is a back view of the electrophoresis wedge-well comb of FIG. 1;

FIG. 5 is a right side view of the electrophoresis wedge-well comb of FIG. 1;

FIG. 6 is a left side view of the electrophoresis wedge-well comb of FIG. 1;

FIG. 7 is a top view of the electrophoresis wedge-well comb of FIG. 1;

FIG. 8 is a bottom view of the electrophoresis wedge-well comb of FIG. 1;

FIG. 9 is a front, top and side perspective view of an electrophoresis wedge-well comb, according to an exemplary embodiment;

FIG. 10 is a back, top and side perspective view of the electrophoresis wedge-well comb of FIG. 9;

FIG. 11 is a front view of the electrophoresis wedge-well comb of FIG. 9;

FIG. 12 is a back view of the electrophoresis wedge-well comb of FIG. 9;

FIG. 13 is a right side view of the electrophoresis wedge well comb of FIG. 9;

FIG. 14 is a left side view of the electrophoresis wedge-well comb of FIG. 9;

FIG. 15 is a top view of the electrophoresis wedge-well comb of FIG. 9;

FIG. 16 is a bottom view of the electrophoresis wedge-well comb of FIG. 9;

FIG. 17 is a front, top and side perspective view of an electrophoresis wedge-well comb, according to an exemplary embodiment;

FIG. 18 is a back, top and side perspective view of the electrophoresis wedge-well comb of FIG. 17;

FIG. 19 is a front view of the electrophoresis wedge-well comb of FIG. 17;

FIG. 20 is a back view of the electrophoresis wedge-well comb of FIG. 17;

FIG. 21 is a right side view of the electrophoresis wedge well comb of FIG. 17;

FIG. 22 is a left side view of the electrophoresis wedge-well comb of FIG. 17;

FIG. 23 is a top view of the electrophoresis wedge-well comb of FIG. 17;

FIG. 24 is a bottom view of the electrophoresis wedge-well comb of FIG. 17;

FIG. 25 is a front, top and side perspective view of an electrophoresis wedge-well comb, according to an exemplary embodiment;

FIG. 26 is a back, top and side perspective view of the electrophoresis wedge-well comb of FIG. 25;

FIG. 27 is a front view of the electrophoresis wedge-well comb of FIG. 25;

FIG. 28 is a back view of the electrophoresis wedge-well comb of FIG. 25;

FIG. 29 is a right side view of the electrophoresis wedge-well comb of FIG. 25;

FIG. 30 is a left side view of the electrophoresis wedge-well comb of FIG. 25;

FIG. 31 is a top view of the electrophoresis wedge-well comb of FIG. 25; and,

FIG. 32 is a bottom view of the electrophoresis wedge-well comb of FIG. 25.
